(57) **CLAIM**

The ornamental design for a bottle, as shown and described.

DESCRIPTION

FIG. 1 is a front perspective view of a bottle in accordance with our design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dashed lines in the drawings depict portions of the bottle that form no part of the claimed design.

The dash-dot lines in the drawings depict boundaries of the claimed design that form no part thereof.

1 Claim, 6 Drawing Sheets
